(57) **CLAIM**

We claim the ornamental design for an electronic module for use with a juvenile product, as shown and described.

DESCRIPTION

FIG. 1 is a front perspective view of an electronic module, mounted to a playard to show an exemplary context, according to our new design;

FIG. 2 is a front perspective view of the electronic module according to our new design;

FIG. 3 is a front elevation view thereof;

FIG. 4 is a back elevation view thereof;

FIG. 5 is a left side elevation view thereof;

FIG. 6 is right side elevation view thereof;

FIG. 7 is a top view thereof; and,

FIG. 8 is a bottom view thereof.

The broken lines immediately and adjacent the shaded areas define the bounds of the claimed design. All other broken lines are for illustrative purposes only. None of the broken lines form part of the claimed design.
